SPRAYING DEVICE

André de Weal, Chicago, Ill., assignor to Leak-proof Sprayer Co., Chicago, Ill., a corporation of Illinois

Application October 20, 1932, Serial No. 638,661

4 Claims. (Cl. 299—97)

This invention relates to a new and improved spraying device and more particularly to a device for manual operation in connection with a liquid receptacle for spraying liquid contained in the receptacle.

The present device is particularly adapted for use in connection with bottles, cans or other receptacles containing fluid which it is desired to discharge in the form of a spray. Examples of such materials are insecticides of various types, lacquers or paints, and polishing fluids to be sprayed on glass, metal or wood. Materials of these types are volatile in character or contain important volatile constituents which should be retained in the material.

Sprayers for similar purposes as developed in the past have comprised a pump to be located in the receptacle and movable pumping members or discharge tubes extending through the cover of the receptacle. These movable members reciprocate through the cover and the loosely fitting contact with the cover has been a point of leakage of liquid, as well as a point through which evaporation may take place. With such devices it is impractical to ship the container with the pump in place therein, as considerable leakage would take place in transit. It has been customary therefore to provide a separate imperforate cover for shipping use. This separate cover is an additional expense and further the separate shipment of the pump or spray device necessitates larger cartons and shipping and display packages. Further, a loss of fluid by evaporation or by spilling if the container is upset, will take place after the pump or spray device has been placed in the container for use.

It is an object of the present invention to provide a new and improved device for spraying liquids.

It is a further object to provide a device of this character adapted to be locked in a receptacle in a manner to prevent leakage from the receptacle.

It is also an object to provide a construction in which the mechanism may be readily locked against leakage and unlocked for use by a single simple movement.

It is an additional object to provide a device which is simple in design and construction and adapted for commercial production and use.

Other and further objects will appear as the description proceeds.

I have shown a preferred embodiment of my invention in the accompanying drawing in

55 which—

Figure 1 is an elevation of the device attached to a bottle, and locked against leakage;

Figure 2 is a transverse vertical section taken on line 2—2 of Figure 1 on an enlarged scale;

Figure 3 is a view on an enlarged scale and similar to the upper portion of Figure 2, but showing the device unlocked;

Figure 4 is a horizontal section on an enlarged scale taken on line 4—4 of Figure 2; and

Figure 5 is an enlarged vertical section taken on line 5—5 of Figure 2.

In the drawing the receptacle 11 has been shown as comprising a glass bottle having the opening 12 surrounded by the neck or flange 13. This flange 13 has screwed thereon the cap 14, 15 which also constitutes the base member for the spray pump construction. The guide member 15 is clamped between the cap 14 and flange 13, and the felt washer 16 and fibre washer 17 serve to maintain a tight fluid-proof connection. The guide member 15 is provided with the sleeve portion 18 which receives the tubular plunger 19. This plunger 19 passes upwardly through the opening 20 in the cap 14. The opening 20, as best shown in Figure 4, is circular in character except for an enlarged portion 21, the purpose of which will appear hereafter.

The plunger 19 carries the collar 22 having the locking lug 23 extending therefrom. Immediately below the collar 22 the plunger 19 carries the rubber packing washer 24. The upper end 25 of this plunger extends laterally and carries a discharge nozzle 26 provided with a small opening 27. Inside of the nozzle 26 is fitted a member 28 which is externally screw threaded and serves to assist in atomizing or finely breaking up the liquid to be discharged from the nozzle. The operating ring 29 extends above the laterally extending portion 25 of the plunger and has its two ends 30 formed to fit about the plunger, these ends being retained in place against the plunger by the collar 22.

As shown in Figure 2, the lower end of the plunger 19 carries the piston 31 having the packing 32 and fitting within the pump cylinder 33. The lower end of the cylinder 33 is crimped at 34 to retain in place the valve seat 35 and also to afford clearances for the passage of fluid into the bottom of the pump chamber. The ball valve 36 fits on seat 35 and is retained in place by cage 37. This cage or spider 37 is retained in place by the spring 38, the other end of which bears against the lower face of the piston 31.

In assembling the device upon a bottle or other container, the pump cylinder 33 and plunger

- 19 are introduced into the bottle and the base member or cap 14 is then secured to the bottle or other container, closing the opening therein. The cap 14 retains the guide member 15 in place, the sleeve portion 18 of this guide member serving to guide the reciprocating movement of the plunger in the pumping operation and to maintain it against lateral displacement. The parts are normally in the position shown in Figure 3.
- 10 When it is desired to ship the article or put it away for future use, the plunger and its associated parts are forced downwardly by pressure upon the ring 29. During this downward movement the parts are turned so that the lug 23 is passed through the extended portion 21 of the perforation 20 in the cap 14. After the lug 23 is passed below the cap, the plunger is turned to bring the lug 23 to the dotted line position of Figure 4. The cap 14 is provided with the depressed portions 39 to restrain the lug against accidental lateral movement such as to bring it in registration with the extended portion 21 of the opening. When the parts are brought to the locked position, which position is shown in Figures 2, 4 and 5, the rubber packing member 24 is compressed against the upper face of the guide member 15 forming a fluid-tight joint about the plunger 19 and between the plunger and the guide member.
- 15 30 To restore the device to operating position it is simply necessary to turn the head of the plunger to bring the lug 23 in registration with opening 21 and as soon as it reaches this position the spring 38 will force the plunger upwardly to the position shown in Figure 3. The plunger may be reciprocated for pumping without depressing it sufficiently to bring the lug 23 below the level of the top of the cap 14. It will be understood that the sprayer is operated by pressing downwardly on the plunger, which may be done by placing the forefinger of the hand through the ring 29, the bottle being grasped in the palm of the hand. Each downward movement of the plunger will force a fine spray through the opening 27 in the nozzle 26. The spring 38 will return the plunger to its upper position so that the operator need merely press down on the ring repeatedly in order to cause the pump and spray to function.
- 20 35 The construction shown is simple in design and adapted for commercial manufacture and use. With the parts in the position shown in Figure 2 the assembly is locked against leakage and the pump and receptacle may be packed in a small carton and shipped without danger of loss. Similarly, if the fluid contained in the receptacle is volatile in character or contains volatile constituents, the receptacle may be locked against evaporation or spilling of the liquid by bringing 40 45 the parts to locked position.

While I have shown one preferred embodiment of my invention it is to be understood that it is capable of modification to meet varying requirements and uses and to fit it to other types of receptacles. I therefore contemplate such changes and modifications as come within the spirit and scope of the appended claims. 5

I claim:

1. In a spraying device, a container, a base member supported on the container, a hollow pump plunger passing through and supported by the base member, a laterally extending discharge end on said plunger above the base member, a pump structure associated with said plunger whereby reciprocation of the plunger forces fluid upwardly through the plunger and out the discharge end, an operating member for reciprocating the plunger extending above the discharge end, said member comprising a metal strip having its ends located adjacent and secured to the pump plunger. 15

2. In a spraying device, in combination with a receptacle having an opening therein, a flange around said opening, a perforate cover secured to said flange, a pump located within the receptacle, 25 a pump plunger extending through the perforation, a guide member having a sleeve fitting about the plunger and having a flange located between the receptacle flange and the cover and retained against the receptacle flange by the cover, packing about the plunger, and means for compressing said packing against the guide member. 30

3. In a spraying device, in combination with a receptacle having an opening therein, a flange around said opening, a perforate cover secured to said flange, a pump located within the receptacle, 35 said pump bearing against the bottom of the receptacle, a pump plunger extending through the perforate cover and resiliently urged upwardly by the pump, a guide member fitted about the plunger and retained in position against the flange by the cover, a packing carried by the plunger, and means carried by the plunger coacting with the cover to maintain the plunger locked in depressed position with the 40 packing compressed against the guide member. 45

4. The combination with a container having a top and having a piston pump mounted therein having a reciprocating hollow discharge piston rod projecting outwardly through the top of the container and having a spring tending to hold said rod in raised position, of a closure for said container, means associated with the discharge rod and adapted to coact with the closure for fastening the discharge rod in lowered position, means for making a tight joint between the discharge rod and the closure. 50 55
